Primary Examiner—Prabhakar Deshmukh

(74) Attorney, Agent, or Firm—Beyer Weaver LLP

(57) **CLAIM**

We claim the ornamental design for a media device, substantially as shown and described.

DESCRIPTION

FIG. 1 is perspective view of a media device showing our new design;

FIG. 2 is a front view for the media device.

FIG. 3 is a rear view of the media device.

FIG. 4 is a top view of the media device.

FIG. 5 is a bottom view for the media device.

FIG. 6 is a right side view for the media device; and,

FIG. 7 is a left side view for the media device.

The broken lines are for illustrative purpose only and form no part of the claimed design.

1 Claim, 3 Drawing Sheets
